United States Patent Office

Des. 178,670

Patented Sept. 4, 1956

178,670

VEHICLE BODY

Charles M. Jordan, Birmingham, William F. Lange, Detroit, and Luther W. Stier, Rochester, Mich., assignors to General Motors Corporation, Detroit, Mich., a corporation of Delaware

Application December 27, 1955, Serial No. 39,480

Term of patent 7 years

(Cl. D14—3)

Figure 1 is a side elevational view of a vehicle body incorporating our new design;

Figure 2 is a top plan view of the vehicle body of Figure 1;

Figure 3 is a front view of the vehicle body of Figure 1;

Figure 4 is a rear view of the vehicle body of Figure 1. The dominant features of our design reside in the full line portions of the drawing.

We claim:

The ornamental design for a vehicle body, substantially as shown and described.
